UNITED STATES PATENT OFFICE.

CHARLES B. RICHARDS, OF HARTFORD, CONNECTICUT, ASSIGNOR TO COLT'S PATENT FIRE-ARMS MANUFACTURING COMPANY, OF SAME PLACE.

DESIGN FOR REVOLVING FIRE-ARMS.

Specification forming part of Design No. 7,933, dated December 15, 1874; application filed December 8, 1874.
[Term of Patent 14 years.]

To all whom it may concern:

Be it known that I, CHARLES B. RICHARDS, of Hartford, in the county of Hartford and State of Connecticut, have invented a new Design for Revolvers; and I do hereby declare the following, when taken in connection with the accompanying drawings and the letters of reference marked thereon, to be a full, clear, and exact description of the same, and which said drawings constitute part of this specification, and represent, in—

Figure 1, side view; and Fig. 2, transverse section.

This invention relates to a design for the shape of the barrel of revolving fire-arms; and it consists in the configuration of the barrel, as shown in the accompanying illustration and hereinafter described.

The barrel is slightly tapering from rear to muzzle, and in transverse section; is of cylindrical form, with the two sides flat, the cylindrical or segmental shape preserved on the upper and under sides of the barrel, as

clearly shown in Fig. 2 of the accompanying illustration. The height from the center line up is defined by the frame, because the sight must be brought up into line with the top of, or sight-groove through, the frame. Reducing or flattening the sides allows a corresponding reduction in the thickness of the frame, and to that extent lightens the arm. The frame, in transverse section, is made to conform to the shape of the barrel, as seen in Fig. 2.

I claim—

The design for revolvers, consisting of the form of the barrel, in transverse section—that is to say, flat upon its two sides and segmental on the top and bottom—the frame of corresponding shape, as shown in the accompanying illustration, and hereinbefore described.

C. B. RICHARDS.
